DESIGN FOR A TOY FIRE ENGINE

Charles John Wood, La Porte, Ind., assignor of
one-half to Gerald W. Seng

Application March 26, 1945, Serial No. 118,706

Term of patent 7 years

(Cl. D34—15)

To all whom it may concern:

Be it known that I, Charles John Wood, a citizen of the United States, residing at La Porte, Indiana, county of La Porte, and State of Indiana, have invented a new, original, and ornamental Design for a Toy Fire Engine, of which the following is a specification, reference being had to the accompanying drawing, forming a part thereof, in which:

Figure 1 is a side elevational view; Figure 2 a top plan view, Figure 3 a front elevational view, and Figure 4 a rear elevational view of a toy fire engine, showing my new design.

I claim:

The ornamental design for a toy fire engine, substantially as shown.

CHARLES JOHN WOOD.
